UNITED STATES PATENT OFFICE

HUBERT DALTON, OF STAMFORD, CONNECTICUT

CURTAIN HOLDER

Application filed July 9, 1928. Serial No. 291,423.

My invention relates to an improved curtain holder for window frames and the like to prevent curtains and similar draperies from obstructing the opening through the frame when the admission of light or air is desired.

An object of the invention is to provide a cheap and simple curtain holder which can be mounted at either side of the opening, 10 without alteration of its construction, and so secured at one end that it can be readily moved out of the way when not needed, or put into operative position; thus serving its intended purpose.

15 The nature of the invention will be made clear from the following description taken with the drawings by which one embodiment of my invention is illustrated. This disclosure, however, is not to be construed as limiting the invention, for I reserve the right to 20 make any changes that do not exceed the scope of the appended claims.

On the drawings,—

Fig. 1 is a perspective view of a curtain holder according to my invention; mounted 25 at the side of a window;

Fig. 2 is a top view of the holder in its operative position;

Fig. 3 is a side view thereof;

30 Fig. 4 is a section on line 4—4 of Fig. 3; and

Fig. 5 is a side view showing the parts when the curtain is released.

The same numerals identify the same parts 35 throughout.

On the drawing, the curtain holder is shown as comprising an arm 1, one end of which is bent over as shown at 2; the other end is attached to a bracket 3 by means of a rivet 4 and this end is provided with a slot 5 through 40 which the rivet extends so that the arm may not only be tilted up and down on this rivet but also move lengthwise as far as the slot 5 will permit.

45 The bracket for mounting the curtain holder arm can be stamped out of a single piece of metal and it comprises a bent-over end or base 6 having apertures 7 therethrough at its opposite ends. On its upper and lower sides 50 the bracket has shoulders 8 from which pro-

ject stops 9 turned out away from the base 6, at the top and bottom edges of the arm 1. The bracket 3 may have an opening 10 for the rivet 4. These two parts or stops 9 are separated by a space equal to the width of the curtain holder bar 1 and the end of this bar adjacent the rivet 4 has a pair of suitable recesses 11. The head of the rivet which engages the bar 1 is enlarged as shown at 12 so as to be bigger than the width of the slot 5.

To mount the holder, fastening devices 13 are inserted through the holes 7 and forced into the side of a window frame 14 or the like. At the top of this frame is a bar 15 to support curtains, one of which is shown at 16. The end 2 is turned away from the window, so that the curtain will not slip off.

In practice when the curtain holder arm is to be secured in operative or braced position, it is manipulated to push the end having the recesses 11 between the lugs 9. The outer end of the bar will then tend to sink of its own weight moving the upper recess 11 so that the upper lug 9 enters it; hence the bar is not only maintained substantially horizontal but cannot be pulled outward with respect to the bracket. If the bracket with the bar in this position is now made fast to the side of a door or window frame, the curtain or drapery attached to the top of the frame can be hung over the bar so as not to obstruct the opening through the frame; as shown in Figure 1. The curtain or drapery can not slip off the bar 1, because of the bent over end 2.

If the holder is not needed, one only needs to lift the outer end to disengage the upper recess 11 from the upper stop 9. The arm can then be pulled outward, the rivet 4 permitting the arm to slide because of the slot 5, and as soon as the adjacent end clears the stop 9 the arm 1 can drop to vertical position at the side of the frame and be supported by the rivet until it is again required for use.

This holder can be affixed to either side of the frame. To put it on the right hand side of the frame in Figure 1, the holder and bracket are simply rotated about the long axis of the arm 1, through half a turn, or 180°. Thus the holder is reversible.

The construction of the holder is therefore 100

exceedingly simple and can easily and cheaply be made in large quantities for domestic and other use. Any occupant of a home or any other building can easily mount it in the required manner by tacks or other fastening devices driven through the openings 7.

I claim:

1. In a curtain holder, consisting of a bracket in the form of an angle having a base 10 joined at one side by a holding plate, said base adapted to be attached to a window frame, said holding plate formed with upper and lower shoulders and having vertically extending stop lugs deflected laterally from the 15 shoulders and forming a central space bounded by the transverse end edges of the stop lugs, said stop lugs lying in a plane parallel to the plane of the base and projecting from the side of the holding plate opposite to that 20 from which the base projects, an arm and a pivot for securing the arm with a lost motion effect to the holding plate and on the stop lug side thereof, to provide for relative movement loosely of the arm in said central space 25 between the transverse end edges of the stop lugs, and means on the arm in the form of a notch for each stop lug adapted to be positively inter-engaged with the transverse end edges of the stop lugs.
- 30 2. In a curtain holder, consisting of a bracket in the form of an angle having a base joined at one side by a holding plate, said base adapted to be attached to a window frame, said holding plate formed with a pair 35 of spaced shoulders and having vertically extending stop lugs deflected laterally from the shoulders and forming a central space bounded by the transverse end edges of the stop lugs which lie in a plane parallel to the plane 40 of the base, an arm and a pivot for securing the arm with a lost motion effect to the holding plate, to provide for relative movement loosely of the arm in said central space between the transverse end edges of the stop 45 lugs and about the pivot as a center, means on the arm for each stop lug for cooperation therewith, adapted for inter-engagement with the transverse end edge of the stop lug, said arm and stop lugs being on the side of 50 the holding plate opposite to that from which the base projects, the bracket and arm designed to be turned through an arc of 180° to provide for use of the holder either at the right-hand side or the left-hand side of the 55 window frame, that one of the stop lugs which comprises the upper stop lug, depending on the position of the bracket and arm, whether on the left-hand side or right-hand side of the window frame, adapted to have 60 its transverse end edge inter-engaged with the arm for sustaining the arm in a position of use.

In testimony that I claim the foregoing as my invention, I have signed my name hereto.
